UNITED STATES PATENT OFFICE.

JULIAN S. NOLAN, OF HIGHLAND PARK, ILLINOIS.

REINFORCED-CONCRETE FLOOR.

1,033,826.

Specification of Letters Patent. Patented July 30, 1912.

Application filed December 26, 1911. Serial No. 667,575.

To all whom it may concern:

Be it known that I, JULIAN S. NOLAN, a citizen of the United States, residing at Highland Park, in the county of Lake and State of Illinois, have invented certain new and useful Improvements in Reinforced-Concrete Floors, of which the following is a specification.

My invention relates to reinforced concrete floors, and the invention has for a primary object to provide a structure subserving the usual ends and purposes of the tile work employed in such constructions which consists, first, of lower tile elements preferably made of vitrified clay or some other suitable material so that they provide an all-tile, or substantially all-tile, plastering surface for the under side of the floor, that is to say, the ceiling of the room below; and second, of sheet metal elements which are placed upon and preferably interlocked or engaged with the tile elements, or some of them, and which constitute with the tile elements box like units that are spaced apart so as to provide channels for concrete and metal reinforcements; the purpose of making the upper elements of sheet metal, instead of making the entire structure of tile as is usual, being, among other things, to lighten and cheapen the structure, to decrease the amount of breakage and the cost of transportation to the place where the floor is constructed, both of the last mentioned two items entering very considerably into the cost of construction when a structure of this sort, as is usual, is made entirely or very largely of tile.

The invention has particular reference to two-way reinforced floors but may be used with some advantage, by suitable obvious modifications, in the construction of one-way reinforced floors.

A further object of the invention is to provide for use in a structure like that above described, or in any other similar structures, a tile element which as manufactured is tubular in form but with the top scored, cut or otherwise weakened along parallel lines so that before being put in place the portions between the weakened lines may be removed from the blocks and used as spacing slabs to space said blocks apart in the floor structure.

The invention has for further objects such other new and improved constructions, arrangements and devices in tiles and in re-

inforced concrete floors as will be herein-after more particularly described and claimed.

The invention is illustrated in a preferred form, and in certain modifications, in the accompanying drawings wherein—

Figure 1 is a fragmentary plan view of a tile structure embodying my invention; Fig. 2, a sectional view taken on line 2—2 of Fig. 1, looking in the direction of the arrows, showing the concrete as well as the tile work; Fig. 3, a sectional view taken on line 3—3 of Fig. 1; Fig. 4, a view in perspective of a preferred form of tile element; Fig. 5, a similar view showing a preferred form of sheet metal element; Fig. 6, a similar view showing a modified form of tile element; Fig. 7, a similar view showing a modified form of sheet metal element; Fig. 8, a fragmentary sectional plan illustrating the application of the sheet metal element shown in Fig. 7 to the tile element; Fig. 9, a view in perspective of a slightly different form of sheet metal element, and Fig. 10, a sectional plan illustrating the application of this element to the tile.

Like characters of reference indicate like parts in the several figures of the drawings.

Referring first to Figs. 1 to 5 inclusive, 20 designates one of the lower or tile elements which as shown consists of a flat base formed with the upstanding webs 21. As shown in Fig. 4 the tile as first manufactured is in the form of an ordinary tubular or partition tile. During the manufacture the top of the tile is scored, cut or otherwise weakened along the lines α by any suitable well known means for accomplishing this result. The tile goes through the kiln scored in this way 25 but with the slabs 22 formed by the scoring adhering to the body of the tile. Preferably the scoring does not completely sever the slabs. Under most circumstances the tile in this form will be transported to the job and the slabs 22 removed when the tile 20 is put in place on the floor centering. By arranging the lines α suitable distances apart the slabs 22 may be used as spacing slabs to space apart the tiles 20. This arrangement 30 is shown in Figs. 1, 2 and 3. A few additional slabs will, of course, be needed when the arrangement is that shown in the drawings. By following this method the manufacture and transportation of the main tiles 35 20 is facilitated and cheapened. The material forming the top member of the tiles 40

which is made unnecessary by the use of the complementary sheet metal elements which will be hereafter described, is utilized to the fullest extent without any waste. As shown particularly in Figs. 1 and 2 the slabs 22 may be arranged to space each of the tiles 20 from the other so as to provide two sets of intersecting channels for the reception of the metal reinforcements 23, 23, and for the concrete 24 which, it will be understood, is filled in plastic condition in the ordinary manner. Coöoperating with the tile elements 20 to form closed box-like units, for the purpose particularly of lightening the floor in the tension zone, are the sheet metal elements 25, a preferred form being shown in Fig. 5. The sheet metal elements extend over the top of the tile elements resting on the webs 21 and are formed with side members or flanges 26 which stand at right angles to the webs 21 and close the open ends of the channels of the tiles. Preferably the side members of the sheet metal elements are formed with inturned rims 27 which are notched as indicated at 28 so that they extend into the spaces between the webs 21 of the tile elements. The tile element 20 is preferably formed with three or more upstanding webs 21, the drawings showing four, the outer pair of webs forming two sides of the closed hollow unit, the inner pair, if the tile is provided with two webs, intermediate the side webs constituting supports for the sheet metal top to keep the same from sagging under the load of the concrete or from being bent in by the workmen who, as a usual thing, have occasion to walk over the tile work before the concrete is poured.

In Fig. 6 I have shown a modified form of tile element 29 which differs from that shown in Fig. 4 in being provided with the flanges or integral spacing elements 30 which make it unnecessary to use spacing slabs in one direction.

In Figs. 7 and 8 I have shown a modified form of sheet metal element 31, the side members or flanges 32 being provided with struck in points or lugs 33 which bear against the upstanding webs 21 of the tile 20.

Figs. 9 and 10 show the sheet metal element which is the same as that shown in Figs. 7 and 8 except that the points or lugs, here designated 34, are turned in the opposite direction.

The above described construction has several distinct advantages over an all tile structure. In some localities at least it is cheaper to make the upper elements of the units of sheet metal than of tile. If the elements of the floor structure have to be transported any considerable distance from the place of manufacture to the place where they are used the freight and cartage on the sheet metal is, of course, much less than on

the tile. The loss by breakage, which is a very considerable item in all tile structures, is very much reduced. An advantage which is more important perhaps than any of these is that my structure is considerably lighter than an all tile structure. As a matter of fact the structure of my invention can be made so that it will weigh only about two-thirds as much as an all tile structure having units of the same dimensions. As a result the dead weight of the floor is lessened by just so much which permits the use of less concrete, metal reinforcements of smaller diameter which, besides effecting a saving in the materials constituting the floor, makes it possible to lighten the supporting structures on which the floor is carried. Thus the cost of the construction of the building as a whole is diminished due to lightening the floor or floors in the tension zone. Furthermore a closer fit can be obtained between a sheet metal element and a tile element, because of the flexibility of the former, than is possible to obtain where the unit is made up of two engaging or interlocking tiles. Tiles cannot be made with anything like geometrical precision. Some irregularity necessarily results from the character of the material used and the fact that more or less shrinkage and distortion is sure to take place in the kiln. When the concrete is poured into the channels, which are formed in part by the flanges or side members of the sheet metal elements, these flanges are pressed snugly against the ends of the tile elements so that leakage of the concrete into the hollows of the units is effectively prevented.

Any of the structures shown in Figs. 6 to 10 inclusive might be used in the arrangements illustrated in the first three figures and it is quite possible that modified forms both of the tile element and the sheet metal element could be devised for accomplishing equivalent results in much the same sort of way. Therefore I do not limit myself to the exact constructions, arrangements and devices shown and described except in so far as certain of the same are made limitations in certain of the claims herein; the intention being to claim both broadly and narrowly whatever patentable invention there may be in the constructions which I have devised in view of the state of the prior art.

I claim:

1. In a reinforced concrete floor, a structure to subserve the purposes of the usual tile work consisting of lower tile elements having flat bases and upstanding webs and upper sheet metal elements having top members resting on said webs and flanges projecting downwardly from the top members and closing the spaces between the ends of said webs, and flat spacing slabs arranged

between the tile elements to space the same apart so as to constitute channels for concrete and metal reinforcements.

2. In a reinforced concrete floor, a structure to subserve the purposes of the usual tile work consisting of lower tile elements having flat bases and upstanding webs and upper sheet metal elements having top members resting on said webs and flanges 10 projecting downwardly from the top members and closing the spaces between the ends of said webs so as to form hollow box-like structures closed on all sides; and spacing elements which space said box-like 15 structures apart to constitute channels for concrete and metal reinforcements.

3. In a structural unit for concrete floors and the like, a tile element composed of a base, side members spaced apart and one or 20 more intermediate supporting members combined with a sheet metal element comprising a top which rests upon said side members and intermediate support or supports, and side members which close the 25 spaces between said side members.

4. In a structural unit for concrete floors and the like, a tile element composed of a base and a plurality of upstanding webs parallel to each other, combined with a sheet metal element comprising a top which 30 rests upon said webs, and side members which close the spaces between the ends of said webs.

5. In a reinforced concrete floor a structure to subserve the purposes of the usual 35 tile work composed of a plurality of units each comprising a lower tile element having a base and a plurality of upstanding webs, and an upper sheet metal element having a top and side members, which latter close the 40 spaces between the ends of said webs; said units providing closed box-like structures arranged in the floor in parallel rows and spaced apart so as to provide two sets of intersecting channels adapted to receive concrete and metal reinforcements. 45
